PHILIP H. GREELEY, OF WASHINGTON, DISTRICT OF COLUMBIA

LOW-FREQUENCY ELECTRIC AMPLIFIER CIRCUITS

Application filed January 16, 1928. Serial No. 247,120.

My invention relates to low frequency electric amplifiers such as are commonly employed for increasing the magnitude of electric currents corresponding to audible tone frequencies. Low frequency amplifiers are best known as applied in telephone repeaters and in the audio amplifiers of radio receiving and transmitting sets.

Where it is desired to amplify audio frequency electric currents a large number of times, as for example, the three or four hundred times commonly attained in the audio portion of radio receivers, a plurality of thermionic tubes are connected in cascade. Such tubes are most conveniently operated from a common source of plate potential which usually is required to have a value in excess of a hundred volts. As a source of high plate potential, batteries have been used but to a considerable extent have been replaced by plate current supply devices operating from electric lighting current. Such devices are provided with a condenser of considerable capacity shunted across its output terminals intended to by-pass alternating currents.

In the desire to obtain high quality audio amplification over the whole musical range, which is considered to extend from 30 or 40 cycles per second to 5,000 or 10,000 cps., suitable units for coupling the audio amplifier tubes have been developed. However, an audio amplifier that will pass the low frequencies effectively often gives trouble when the tubes are operated from a common source of plate current having considerable resistance or depending upon a condenser for by-passing the alternating currents. The reactance of a condenser increases with decrease of frequency, and, at the low frequencies, the by-pass condenser reactance is not low enough to prevent coupling troubles between the several tubes working in the amplifier.

Several methods of reducing the magnitude of these coupling effects in low frequency amplifiers have been devised. Some methods reduce the trouble by reducing or cutting out the amplification of the low frequencies, which obviously is detrimental to best quality amplification. Sometimes voltage regulator tubes having very low alternating current im-

pedance are employed, but such tubes waste current and are expensive. Partial separation of the individual amplifier tube circuits by means of separate choke coils and condensers represent considerable expense if 55 adequate values and sufficient number are used. However, these methods are successful only in reducing the magnitude of the disturbing effects.

An object of my invention is to provide a 60 method and apparatus that can be used to balance out completely the coupling effect between each pair of tubes.

Another object is to provide a circuit and apparatus for an audio amplifier that will be 65 free from peaks of excessive amplification caused by regeneration.

A further object is to provide an audio amplifier that is capable of amplifying the lowest useful audio frequencies with perfect 70 smoothness.

Still another object is to reduce the number and values of such auxiliary apparatus as chokes and by-pass necessary to obtain desired results.

An additional object is to provide a radio receiving set in which the vacuum tube filaments may be heated by alternating current with satisfactory elimination of alternating current hum.

Other objects include the provision of 80 means for reducing the possibility of undesirable pick-up of relatively high frequency currents in an audio amplifier and means for gaining generally improved performance 85 from a radio receiving set or audio amplifier.

With these objects and other objects hereinafter described in view, my invention resides in the method, apparatus and circuit 90 hereinafter described and claimed.

Referring to the drawings:

Figure 1 is a schematic diagram showing a circuit arrangement for a pair of tubes operated from a common source of plate potential, this arrangement being a form to which my balancing method is readily applicable.

Figure 2 is a diagrammatic representation of the circuit constants of Figure 1 adapted 100

to illustrate the mathematical considerations involved.

Figure 3 is a schematic diagram for one practical audio amplifier circuit in which my invention may be applied.

Figure 4 is a schematic diagram showing an alternating current filament lighting circuit suitable for use with an audio amplifier of the type shown in Figure 3 and additional radio amplifying tubes.

Figure 5 is similar to Figure 4 except that provision is made for lighting the filaments of the detector and first audio tubes from rectified and filtered current.

Figure 6 is a schematic diagram showing coupling means for a pair of radio amplifier tubes, said coupling means being adapted to balance out low frequency disturbance in a radio frequency amplifier.

Figure 7 shows schematically the elements of Figure 6 that are effective in the balancing out of low frequency disturbance, such as may be caused by heating of amplifier tube filaments on alternating current.

Figure 8 represents diagrammatically the relative direction of instantaneous signal and hum voltages that may be present in a radio frequency amplifier of the type shown in Figure 6.

Figure 9 is a schematic diagram showing a modified form of my balancing method applied in a resistance or impedance coupled audio amplifier, and

Figure 10 is a sketch indicating a preferred arrangement of elements in an amplifier and showing means for practically eliminating undesirable pick-up of relatively high frequency currents.

In the drawings, amplifying repeaters T^1 and T^2 , here shown as the familiar three element thermionic tubes, are coupled together by an audio coupling unit. This unit may comprise a plate impedance or choke coil L^1 , a plate circuit resistance R^3 , a coupling condenser C^1 , a grid impedance L^3 , a grid circuit resistance R^5 and a connection through a grid bias battery CB . A primary L^2 of an audio transformer L^2 , L^4 and a resistance R^4 are shown connected in the plate circuit of tube T^2 .

Tubes T^1 and T^2 have their plates maintained at a positive potential with regard to their filaments by means of a plate current supply device or batteries connected across the terminals B minus and B plus. A by-pass condenser C^2 and a resistance R^6 or their equivalent are usually connected across these B terminals.

With regard to a signal voltage E_s applied across the grid and filament of tube T^1 , the amplifier operates in the normal manner familiar to those skilled in the art, and the amplified signal voltage AE_s is available across the secondary L^4 of audio transformer L^2 , L^4 . This invention is not primarily con-

cerned with a detailed consideration of the means used for amplifying the signal voltage E_s , the straight amplification of signal voltages being quite well understood at the present time.

This invention resides mainly in the method, apparatus and circuit used to eliminate or reduce below a harmful value the effect of an alternating current potential E effective across the common B terminals supplying plate current to the tubes. This alternating current potential E may be represented as due to a generator G which may be effective because of incomplete filtration in the

plate current supply device, but more commonly is effective because of the relatively heavy current fluctuations of the end audio tube of such amplifiers as are intended for the operation of loud-speaking reproducers. End audio tubes commonly have an instantaneous plate current variation of from 5 to 35 milliamperes, and instantaneous potential fluctuations of a hundred volts. In an amplifier in

which a signal magnification of around 300 times is attained, if as little as one three hundredth of the output voltage is fed back into the input, the amplifier may oscillate or may be inoperative. In an audio amplifier that is capable of passing the lowest useful audio frequencies, it is a very difficult matter to keep the alternating current voltage E represented as due to the fictitious generator G below an appreciable value.

According to my invention, I recognize the presence of an A. C. potential E and have devised a method, apparatus and circuit by which this potential E may be balanced out completely or to a degree that is satisfactory for practical purposes. In using my method of balancing out the effect of the A. C. potential E , it is most practicable to consider the amplifying tubes by pairs and so determine the circuit constants with respect to the A. C. plate impedance of the first tube of the pair and the amplification attained between the output of the first tube and the output of the second tube that the effect of the A. C. potential E may be balanced out completely or to the degree desired.

With reference to Figures 1 and 2, it is well understood that the external impedance, Z^1 (modified by Z^3) and Z^2 in the plate circuits of tubes T^1 and T^2 should exceed the A. C. plate impedances R^1 and R^2 of said tubes at all frequencies which are to be amplified effectively.

In fact, the external impedance should be three or more times greater than the tube plate impedance for practically distortionless amplification. As is well understood, impedance Z^1 is the vector sum of the inductive reactance X^1 of choke L^1 and the resistance R^3 ; similarly, Z^2 is the vector sum of X^3 (reactance of choke L^3) and R^5 , and Z^2 is the vector sum of X^2 (reactance of transformer primary L^2) and R^4 . These imped-

ances will be large relative to the reactance of by-pass condenser C^2 and parallel resistance R^3 at any useful audio frequency. My method of balancing may be made practically independent of the effective reactance across the B terminals, so that this reactance or impedance will be considered only where its effect is of importance.

To consider the theory of my method of balancing, suppose that the A. C. voltage E causes an effective voltage E^1' to be applied across R^1 , the filament to plate impedance of tube T^1 . E^1' will cause an effective voltage E^1 to be applied across the grid and filament of tube T^2 . With the circuit arrangement of Figure 1, E^1 may be made nearly the same as E^1' for all useful audio frequencies to be passed by the amplifier, though with different circuit arrangements E^1 may be made greater or less than E^1' . E^1 is then amplified and reversed in phase by tube T^2 , giving the voltage μE^1 which is the same as the amplified voltage aE^1' , considering "a" the amplification obtained in the coupling unit and tube T^2 . It will be observed that the A. C. voltage E also causes an effective voltage E^2 to be applied across R^2 , the filament to plate impedance of tube T^2 , in addition to voltage E^1' applied across R^1 . In using my method of balancing, I arrange the circuit and select constants so that aE^1' is equal or approximately equal to E^2 and opposite in direction. With this condition maintained either for all audio frequencies or for those low enough not to be effectively by-passed by the condenser and resistance across the "B" terminals, it will be seen that an A. C. voltage variation E will set up a zero net effective voltage across R^2 , the filament to plate impedance of tube T^2 , and no current due to E will flow in the primary L^2 of audio transformer L^2, L^4 .

The important considerations in my method of balancing are the A. C. plate resistances R^1 and R^2 of tubes T^1 and T^2 respectively, the effective external impedances in the plate circuits of the tubes, and the amplification obtained in the coupling unit between the tubes and the amplification constant or " μ " of tube T^2 .

In considering the selection of circuit constants for a practical application of my invention, it appears desirable for the sake of simplicity to eliminate Z^3 from consideration. It is practicable and preferable to make Z^3 have a high impedance relative to R^1 so that the effective impedance of R^1 in parallel with Z^3 including the reactance of condenser C^1 will be from 0.9 to 1 times the plate impedance R^1 alone at any useful audio frequency. This may be done readily by making choke L^3 have a high inductance value or using a high resistance R^5 , or both in series. The capacity of condenser C^1 is preferably made rather large, a capacity of

0.5 mfd. being practicable. Thus, by making Z^3 large, its effect would not be of great importance in determining the balance necessary in the usual amplifier, though for exceptionally accurate balance, the effect of Z^3 would enter into computations.

Then neglecting Z^3 for simplicity, an A. C. voltage E across the B terminals will cause a voltage E^1' to be effective across R^1 in which case

$$E^1' = \frac{R^1 \times E}{R^1 + Z^1} \quad (1)$$

where the resistances and reactances appearing in the denominator are added as vectors.

Similarly, the A. C. voltage E produces an effective voltage E^2 across R^2 , in which case,

$$E^2 = \frac{R^2 \times E}{R^2 + Z^2} \quad (2)$$

The condition for balancing out the effect of voltage E is that aE^1' , which is the voltage E^1' amplified and reversed in phase, shall be made equal to E^2 . For simplicity, the right hand member of Equation (1) above may have both numerator and denominator multiplied by $R^2 R^1$ without changing its value. This gives

$$E^1' = \frac{R^2 \times E}{R^2 / R^1 (R^1 + Z^1)} \quad (3)$$

Equations (2) and (3) have the same numerator, so, to make E^1' a fraction $1/a$ (one over the amplification) times E^2 , the denominator in (3) will be made "a" times the denominator in (2). A simple, yet reasonably accurate, expression for the condition of balance is

$$R^2 / R^1 (R^1 + Z^1) = a \times (R^2 + Z^2) \quad (4)$$

where resistances and reactances are added as vectors.

It will be noted that Equation (4) may be made to hold independent of frequency if the inductances and resistances entering into the expression for Z^1 and Z^2 are made to have suitable relative values. However, it may be satisfactory to obtain my balancing effect only for a limited band of frequencies, for example, only such low audio frequencies as are passed by the amplifier yet are not effectively by-passed by the impedance across the "B" terminals. For low frequencies, the resistance components R^3 and R^4 of impedances Z^1 and Z^2 are of relatively greater importance than the reactive components X^1 and X^2 .

Although it is preferable to balance an amplifier made in accordance with the ideas of this invention accurately, good results are obtainable in many cases with only an approximate balance. Without understanding the principles explained in this specification, it would be unlikely that one skilled in the art would select tubes and circuit constants

and arrange a circuit giving even approximately the results I obtain. It is true that resistance coupled units, impedance coupled units, and transformers are used in audio amplification, also various combinations of these different units; yet, the selection of these different units has rested mainly upon the merits of the different types with respect to their ability to translate signal voltages, and without the idea of balancing out the effect of voltage fluctuations across the "B" terminals supplying current to the amplifier tubes. Anyone building an amplifier without the idea of balancing out the effect of a voltage E would in all probability fail to select values satisfying Equation (4) above within 60 per cent.

A practical application of my invention in an audio amplifier may utilize the schematic circuit diagram shown in Figure 3. In this diagram, tubes T^1 and T^2 have their circuits arranged as explained above with reference to the circuit of Figure 1. Tube T^3 has its input connected across the secondary L^4 of transformer L^2 , L^4 , though a condenser C^5 is preferably used instead of a direct connection to the tube filament so that a grid bias potential may be applied through a suitable resistance R^7 . Tube T^3 is coupled to an end audio tube T^4 by means of a coupling condenser C^8 , plate circuit choke L^5 and resistance R^8 , and grid circuit choke L^6 and resistance R^9 , condenser C^8 being used across the "B" terminals. Tube T^4 has in its output circuit a choke L^7 suitable for carrying direct current to the plate yet offering a high impedance to alternating currents. C^4 represents a coupling condenser to the inductive load L^8 which may be the winding of a loudspeaker or other sound or signal reproducer. Any suitable source of plate potential may be connected across the terminals B plus and C minus, and a suitable tapped resistor R^{10} may be connected across the same terminals so that desired grid bias and plate potentials for the different tubes may be obtained readily.

In the amplifier circuit of Figure 3, tube T^1 may be a detector in a radio receiving set and tube T^2 the first audio amplifier. My method of balancing is of greatest importance as applied to these two tubes, since the output of these tubes is greatly amplified. It is preferable, also, to balance the circuits of tubes T^3 and T^4 at least partially.

In addition to the balancing effect I obtain, I may use means to reduce the magnitude of plate voltage variations at suitable points in the circuits. Such means may comprise a choke coil and by-pass condenser as indicated by L^{10} and C^7 , also, L^9 and C^6 . Although an audio amplifier that is balanced in accordance with my invention will be free of many troubles without the use of such chokes as those indicated by L^9 and L^{10} , their use in

some cases may be beneficial. A voltage variation of large magnitude across the "B" terminals of such tubes as are operated at moderate or low plate voltages should preferably be prevented. Radio frequency tubes, detectors and first audio tubes are usually operated at moderate plate voltages and their plate supply may be filtered as indicated in Figure 3.

It has been said that a voltage variation across a plate current supply device may be due to imperfect filtration but more commonly is caused by the heavy current variations in the plate circuit of the last audio tube of an amplifier. The arrangement shown in the plate circuit of tube T^4 , Figure 3, is desirable for the reason that the relatively large alternating currents are in the main choked out before being applied across the by-pass condenser C^8 and resistance across the "B" terminals. Therefore, voltage fluctuations across the "B" terminals will not have as great magnitude as might otherwise be the case.

Although I have given the conditions that must be satisfied to apply my balancing method to an audio amplifier, it may be necessary to keep in mind some idea of the lowest or cutoff frequency of signal that passes through the amplifier. The cutoff frequency is, of course, not one definite frequency but rather the frequency below which the amplification falls rapidly. The cutoff frequency will be determined by the characteristics of the tube coupling devices. In the impedance coupled stages shown in Figure 3, the frequency cutoff may be set readily at about the desired point by selecting values for the grid chokes L^5 and L^6 and by using condensers C^9 and C^{10} . The cutoff frequency is of importance in that the balancing method needs to hold only down to the cutoff frequency and up to the frequencies not effectively bypassed by a capacity across the plate current supply unit.

In practical audio amplification, an amplifier that will pass notes as low as 50 or 60 cycles per second may be considered very good. With my method of balancing, an amplifier passing notes down to 50 cps. without noticeable trouble may be constructed without great expense. Such by-pass condensers as are necessary are not numerous nor great in value, values of about 2 microfarads being suitable for most purposes. However an amplifier passing notes down to 20 or 30 cps. can be made quite successfully and without great additional expense.

Tubes used in an amplifier built in accordance with my invention may be of the usual general purpose types having an amplification constant of from 5 to 10 and a plate impedance of from 10,000 to 25,000 ohms. But better results may be obtained by using

power or semi-power tubes for T^2 and T^4 , while T^1 and T^3 may be of the general purpose type or the high voltage amplification type. Four element tubes may be used with suitable connections for the added element. Use of power tubes at T^2 and T^4 will obtain best results from an audio transformer or loud-speaking device, and the low plate impedance of such tubes permits the condition of balance to be satisfied with a greater effective direct current plate voltage on tubes T^1 and T^3 .

I have described my method of balancing with regard to the plate circuits of amplifier tubes operating from a common source of plate current supply, where the possible interaction effects are of greatest importance. If necessary, however, a somewhat similar balancing system may be used in the grid circuits where the source of grid bias voltage for the several tubes is common as shown in Figure 3.

It will be understood that I do not limit myself to the particular circuit arrangements shown, though the circuit of Figure 3, with possibly minor variations, is one that is most practicable. Aside from the balancing effect possible in this particular circuit, the coupling units are particularly well suited to the conditions existing in the different portions of the amplifier. Tube T^1 , if working as a detector, will usually have a high plate impedance and the external plate impedance should be exceptionally high; an audio transformer will work best with its primary in the plate circuit of a tube used as an amplifier and where the signal voltage is not of greatest magnitude, that is, most transformers will show overload distortion on strong signals; and a dual or double impedance coupler is used as a coupling unit where the strongest signal transfer takes place, the load capacity of a dual impedance of moderate cost being known to be exceptionally high. Dual and double impedance coupling units are known in the art, the term "dual" being applied when chokes L^1 and L^3 or L^5 and L^6 , Figure 3, are wound on the same core and are inductively coupled, and the term "double" is generally used when the chokes are wound on separate cores and are not inductively coupled. Either dual or double impedance coupling devices may be adapted to meet requirements in carrying out my invention. The relatively high resistances R^3 and R^5 , Figure 3, do, however, change the action of such coupling devices as have been designed with the sole idea of functioning as audio coupling units, such as the "tuned impedance couplers" designed to afford increased amplification near the resonant frequency. It is obvious that suitable coupling units meeting the requirements of this invention may be enclosed in a single case with four or five connecting terminals.

Where an amplifier of greater power han-

dling ability than that afforded by the circuit of Figure 3 is desired, the well known push-pull system may be used. If tubes T^3 and T^4 are each replaced by a pair of tubes working in the push-pull manner, my balancing system may be applied to both halves of such an amplifier.

In addition to eliminating trouble from plate supply voltage variations, an amplifier constructed in accordance with the principles disclosed herein will prove advantageous where the filaments of some or all of the amplifier tubes are lighted on alternating current. It is well known that tubes lighted by alternating current tend to have an A. C. variation in plate current which produces an audible hum in a loudspeaker or other reproducing device. The causes of hum have been studied and tubes have been developed to reduce this hum to a minimum. The main hum is perhaps caused by variations of filament temperature which result in a hum frequency of double that of the filament lighting current.

If a pair of tubes connected in cascade and having their filaments operated on alternating current are considered the hum in both tubes will be in phase but the amplified hum from the first tube will oppose the hum in the second tube if the circuit arrangement is similar to that shown in Figure 1. If the hum voltage effective across the plate circuit of the first tube is kept relatively low in magnitude so that when amplified it will approximately or exactly equal the hum effective across the plate circuit of the second tube, the hum voltage will cancel out in the output circuit of the second tube. It is much easier to reduce the hum effect to a desired value than eliminate it entirely, variation of the hum magnitude being readily accomplished either by changing the type of tube or changing the tube operating conditions.

Suitable filament circuits for a six tube radio receiving set for A. C. filament heating are shown in Figures 4 and 5. In Figure 4, tubes T^{10} and T^{11} are radio frequency amplifiers, T^1 is a detector tube, T^2 , T^3 and T^4 are audio amplifier tubes. These tubes are preferably of different types, each type being particularly suitable for its specific purpose. It is common to employ tubes having low voltage, high current filaments, with the filaments themselves serving as electron emitters, for radio and audio amplifiers operated on A. C. The detector is more commonly of the heater type, in which the filament serves to heat an auxiliary electrode which serves as electron emitter; generally, these different tubes require different filament voltages which are supplied from a step-down transformer having a plurality of secondary windings. The last tube is preferably of the current amplifier or power type. The detector and audio amplifier tubes will have their grid and plate

70

130

circuits arranged in corresponding manner to that shown in Figures 1 and 3.

Figure 5 shows a circuit similar to Figure 4 except that the detector T^1 and first audio tube T^2 have their filaments in series and are lighted by direct current either from a battery or from the plate current supply device. Since the detector T^1 and first audio tube T^2 usually are required to operate only on weak signal voltages, small tubes having low current filaments are satisfactory and can be lighted from the plate current supply device without placing a severe load on said device. It is well known that the elimination of hum effects in the output of a vacuum tube operated as a detector is very difficult, yet is of the greatest importance. Greater satisfaction is often obtained by operating the detector on direct current rather than alternating, and where the detector is so operated, there is little added difficulty operating the first audio tube from the same current source. The detector and first audio tubes, when operated from the same filament current supply, are readily paired as shown in Figure 1 to eliminate undesirable effects.

Although it might not seem particularly important to eliminate hum effects present in a radio frequency amplifier, a careful consideration will show that a slight modulation effect of a hum will be detected and greatly amplified, therefore proving serious. As is well known, modulation will be relatively greater on strong signals than weak signals, and a powerful radio frequency amplifier will be most subject to the modulation effect of an A. C. hum. Most radio frequency amplifying circuits are not suitable for eliminating the effect of a low frequency hum or other disturbance, but the high frequency amplifying circuit described in my co-pending application for U. S. Letters Patent, Serial Number 150,576, filed November 24, 1926, entitled "Radio frequency amplifying apparatus", has been found to eliminate or reduce the effect of an A. C. hum when the amplifier tubes are lighted on A. C.

The essential circuit of my radio frequency amplifier is shown in Figure 6. Since a low frequency alternating current or A. C. hum is not affected appreciably by the presence of the high frequency tuning inductances, and since the capacity of tuning condenser C^{13} is small relative to the capacity of the mutual condenser C^{12} , the circuit is re-drawn in Figure 7, with these elements omitted. It will be seen that tubes T^{10} and T^{11} are capacitively coupled by condenser C^{11} . If the radio frequency choke L^{11} has considerable resistance or reactance toward the hum frequency, or if a resistance R^{12} is provided, and if C^{11} has considerable capacity relative to mutual condenser C^{12} , an appreciable portion of the hum voltage effective across the plate circuit of tube T^{10} will be applied across the grid

and filament of tube T^{11} . It is obvious that circuit constants may be selected so that a fraction equaling $1/($ amplification constant of tube T^{11}) of the hum voltage effective across the plate circuit of tube T^{11} will be applied across its input. Since the phase of this hum voltage is reversed in tube T^{11} , the fractional hum voltage when amplified will equal and oppose the normal hum voltage effective across the output of tube T^{11} , thereby eliminating the hum effect. In Figure 8 is shown the direction of the signal and hum voltages effective in a circuit of the type shown in Figure 6. S indicates the primary radio frequency signal voltage, S' the secondary RF signal voltage and aS' the amplified RF signal voltage effective across the plate circuit of tube T^{11} . The hum voltage H effective across the plate circuit of tube T^{10} is reduced or attenuated to H' across the input to tube T^{11} and then amplified to aH' which should equal and oppose the hum voltage H effective across the plate circuit of tube T^{11} .

Although the elimination of A. C. hum is somewhat different from the elimination of the effects of an A. C. component in a common source of plate potential, it will be seen that both may be accomplished simultaneously wholly or in part by similar circuits and circuit constants. The improvement in performance of a radio receiving set or audio amplifier which is designed in accordance with the principles discussed herein is very noticeable, and satisfactory operation is obtainable with sources of plate and filament current that ordinarily cannot be used satisfactorily.

The radio frequency amplifying circuit of Figure 6 has been found useful in the reduction of undesirable effects present in the usual frequency amplifier circuits. As explained in my co-pending application, Serial Number 150,576, mentioned above, substantially uniform efficiency and selectivity in the amplification of radio frequency signals is obtainable by the use of this circuit in one or more stages over the tuning range covered by the tunable circuit S^{11} , C^{12} and C^{13} . A condenser C^{14} is preferably connected across the plate current supply to the radio frequency amplifier tubes. Condenser C^{15} and resistance R^{12} , or a suitable reactance coil, offer convenient means for regulating the value of a low frequency A. C. voltage translated from tube T^{10} to tube T^{11} . This low frequency A. C. voltage may be caused by A. C. heating of the filament of tube T^{10} . As suggested in my co-pending application referred to, a grid bias voltage for the RF amplifier tubes may be supplied through a relatively high resistance R^{11} or choke coil, or both in series. Considerable resistance at R^{11} appears to have a desirable effect in that the radio amplifier tends to block and reduce the amplification of

excessively strong signals and atmospheric strays or static. Unusually steady reception of fading signals and relative freedom from noise have been obtained with this type of amplifier, particularly when a plurality of 5 radio amplifier stages are employed. Where more than one stage of this type is used, it appears to be desirable to make the radio frequency chokes L^{11} in the different stages somewhat different in inductive value so that 10 trouble from undesirable resonance effects may be avoided. The results obtained by the use of the radio amplifier circuit of Figure 6 in combination with an audio amplifier circuit similar to Figure 3 in a complete radio 15 receiving set with its power supply have been particularly satisfactory as to tone quality, even and steady performance at different radio frequencies covered by the tuned circuits, and relative freedom from noise of any kind accompanying reception.

A modified application of my balancing idea is shown in Figure 9, which represents a resistance coupled audio amplifier. T^1 may 20 be a detector having a grid condenser C^{31} and resistance leak R^{39} . The use of a detector output by-pass condenser C^{25} and a radio frequency choke L^{25} of suitable values is desirable. Plate circuit resistors R^{21} , R^{22} , R^{23} , and 25 R^{24} having any suitable values, coupling condensers C^{21} , C^{22} , C^{23} and C^{24} having suitable capacities, and grid circuit resistors R^{31} , R^{32} and R^{33} having suitable resistances are provided for the several tubes. Suitable impedance 30 coils may be substituted for the resistances, or may be used in addition to the resistances as shown in the circuits of the end audio tube T^4 where chokes L^{33} and L^{34} are provided. In the case of a power tube, which 35 is preferable for last audio tube T^4 , the relatively large grid swing and the high plate current limit the circuit resistance permissible, and choke coils having high A. C. impedance but relatively low D. C. resistance are preferable 40 to pure resistances.

Comparing Figure 9 with Figures 1 and 2, T^1 and T^2 of Figure 9 may be considered as a pair in which the external plate resistance or impedance Z^1 is divided in two sections, 45 one formed by R^{21} and one by a resistance R^{34} , a by-pass condenser C^{27} being provided as indicated. Similarly, tubes T^2 and T^3 are paired, the extra resistance R^{35} and condenser C^{28} being provided. Also, T^3 and T^4 are 50 paired, with resistance R^{36} and condenser C^{29} added. C^{30} is a by-pass condenser across the plate current supply. Practical values for condensers C^{27} , C^{28} , C^{29} and C^{30} are approximately 2 microfarads each, and resistances 55 R^{34} , R^{35} and R^{36} may each be of the order of 20,000 ohms.

If an A. C. voltage effective across condenser C^{28} is considered, a portion of this voltage will be effective across the internal 60 plate impedance of tube T^2 and a much

smaller portion of this voltage should be applied across the internal plate impedance of tube T^1 . Instead of making the external plate resistance or impedance of tube T^1 greatly higher than resistance or impedance 70 R^{22} , the resistance R^{34} in series with the reactance of condenser C^{27} is employed so that the voltage effective across C^{27} is reduced as compared to that applied across C^{28} , the degree of reduction depending upon the resistance R^{34} and the reactance of condenser C^{27} 75 at the frequency of the voltage. The voltage effective across C^{27} is further reduced as applied across the internal plate resistance of tube T^1 . The portion of the voltage effective 80 across condenser C^{28} applied across the internal plate impedance of tube T^1 should be only a fraction of the voltage applied across the internal plate impedance of tube T^2 , this fraction being equal to or less than the reciprocal of the amplification gain between the 85 output circuits of tubes T^1 and T^2 for any frequency within the range amplified.

It will be observed that the phase of a signal voltage is reversed in the step from one tube to the following tube in the amplifier 90 of Figure 9. Therefore, the voltage applied by an A. C. component E in the plate current supply across the internal plate impedance of a preceding tube, when amplified, opposes 95 a similar voltage applied across the internal plate impedance of the next following tube. In designing this amplifier, E/w may be considered the A. C. voltage effective across 100 the internal plate impedance of the first tube, then

$$\frac{E}{x} - \frac{aE}{w} \quad (5)$$

may be considered the sum of the voltages 105 E/x applied through plate circuit coupling and aE/w applied through amplification across the internal plate impedance of the second tube. In a similar manner,

$$\frac{E}{y} - bE\left(\frac{1}{x} - \frac{a}{w}\right) \quad (6)$$

which is the sum of the voltages applied 115 across the internal plate impedance of the third tube through the several couplings. Likewise,

$$\frac{E}{z} - cE\left[\frac{1}{y} - b\left(\frac{1}{x} - \frac{a}{w}\right)\right] \quad (7)$$

may be considered the sum of the voltages 120 applied across the internal plate impedance of the fourth tube through the several couplings. Letters a , b and c represent the amplification gain between successive tubes and w , x , y and z represent the attenuation factors indicating the portion of the voltage 125 E effective across the internal plate impedance of the several tubes. In Equations 5, 6 and 7, if the fraction of E written to 130

the left of the first minus sign is always greater than the expression to the right of said minus sign, the amplifier will be free from regeneration.

- 5 In the amplifier represented in Figure 9, the approximate resistance values indicated may be found suitable for use with tubes giving an amplification of about 10 per stage at 30 cycles per second, condensers of 2 mfd. 70
10 capacity being used at C^{27} , C^{28} , C^{29} and C^{30} . Such condensers in combination with resistors R^{34} , R^{35} , and R^{36} form a sectional filter attenuating an A. C. voltage of 30 cps. frequency to about one tenth in each section. 75
15 Below this frequency the attenuation decreases and the coupling elements between the tubes should be selected so as to decrease the amplification between tubes accordingly. Tubes T^1 , T^2 and T^3 are operated as voltage 80
20 amplifiers which may work effectively with a plate current of 1 millampere or less. Considering these tubes to have plate currents of 1 millampere, the voltage drop in R^{34} will be 20, in R^{35} will be 40, and in R^{36} will be 60. Tube 85
25 T^4 is preferably a power tube having a plate current of about 20 milliamperes, which would give a voltage drop of 80 in resistance R^{24} . The voltages 135, 155, 195, and 255 represent practical values which might exist at the different 90
30 points in this amplifier.

It may be pointed out that a sectional filter of the type comprising resistances R^{34} , R^{35} , and R^{36} with suitable condensers may be no more expensive to construct than a single 95
35 filter for use on the detector plate voltage supply alone, both filters giving the same attenuation at the detector. An equivalent filter may be arranged with impedance coils instead of resistances. It is preferable to 100
40 provide a separate filter and voltage divider for the plate potential for radio frequency amplifier tubes, as indicated by choke L^9 resistance R^{37} and condenser C^{26} .

In the above description, possible phase 45
45 angle differences have not been considered, though it is desirable to keep these in mind when designing an amplifier.

Since this invention is intended to provide a generally improved amplifier, a method of 50
50 reducing any tendency toward undesirable pick-up of relatively high frequency currents is represented in Figure 10. As is well known, high frequency pick-up or feed-back in an audio-amplifier often results in the production of a high pitched whistle or hiss. Wherever it may be necessary to make relatively long leads connecting a unit such as the audio transformer L^2 , L^4 of Figure 3 to tube sockets TS^1 and TS^2 and associated apparatus, it is desirable to insulate and twist 55
60 together the leads as indicated in Figure 10, thereby equalizing pick-up in the going and return wires. By-pass condensers C^5 and C^7 preferably are located close to their respective tube sockets. Where a volume control, 65

which may be a variable resistance, is used, considerable length of wire often is necessary to permit the volume control to be located conveniently, and these necessary wires are preferably insulated and twisted together. If the connecting wires are of about #18 B & B gauge or smaller, and the insulation is comparatively thick, the shunt capacity introduced across the transformer windings or other coupling unit is not likely 70
75 to be sufficient to cut off the amplification of any desirable high audio frequencies. Although twisted leads are commonly employed for carrying alternating current power, as for filament lighting current in 80
85 radio receivers, the use of such twisted leads in combination with by-pass condensers suitably located for carrying audio currents has not been generally known, yet improved results are gained thereby.

In the following claims, the terms "alternating currents" or "potential fluctuations" are used without particular distinction between voltage and current. It is, of course, understood that electric amplifiers are usually worked as voltage amplifiers and the consideration of voltages may be most important except in the last or output stage. A fluctuating direct current may be considered as a steady direct current having superimposed thereon alternating current. In this invention, the alternating currents or potential fluctuations considered are mainly of an audio frequency range and particularly of a low audio range from approximately 20 to 100
100 cycles per second.

Having thus described my invention what I claim is:

1. In electric signal amplifying apparatus having amplifying tubes connected in cascade and operated from a common source of plate potential, means for eliminating from the signal output of a pair of tubes undesired low frequency alternating currents present across the plate supply which comprises a circuit arrangement for said pair of tubes giving a reversal of phase of signal currents between their output circuits with impedances of such relative inductive and resistive values with reference to said undesired alternating currents, between the plates of said pair of tubes and a common point of connection to the plate current supply as to make the plate circuits impedance of the first tube between its cathode and said common point as many times greater than the plate circuit impedance of the second tube between its cathode and said common point as the amplification factor between the output circuits of said tubes.

2. In electric signal amplifying apparatus having amplifying tubes connected in cascade and operated from a common source of plate potential, means for eliminating from the signal output of a pair of tubes undesired

low frequency alternating currents present across the plate supply which comprises a circuit arrangement for a pair of tubes giving a reversal of phase of signal currents between their output circuits with impedances of such relative inductive and resistive values with reference to said undesired alternating currents, between the plates of said pair of tubes and a common point of connection to the plate current supply as to make the plate circuit impedance of the first tube between its cathode and said common point as many times greater than the plate circuit impedance of the second tube between its cathode and said common point as the amplification factor between the output circuits of said tubes.

5 10 15 20

3. In electric signal amplifying apparatus having amplifying tubes connected in cascade and operated from a common source of plate potential, means for eliminating from the signal output of a pair of tubes undesired low frequency alternating currents present across the plate supply which comprises a circuit arrangement for said pair of tubes giving a reversal of phase of signal currents between their output circuits with impedances of such relative inductive and resistive values with reference to said undesired alternating currents, between the plates of said pair of tubes and a common point of connection to the plate current supply as to make the plate circuit impedance of the first tube between its cathode and said common point as many times greater than the plate circuit impedance of the second tube between its cathode and said common point as the amplification factor between the output circuits of said tubes, in combination with similar means for eliminating from the signal output of a second pair of tubes similar undesired low frequency alternating currents and means for coupling the signal output of the first pair of tubes to the input of the second pair of tubes.

25 30 35 40 45

4. In a radio receiving set having a detector tube and audio amplifying tubes connected in cascade and operated from a common source of plate potential, means for filtering the plate current supplied to detector and first audio tube coupled to detector separate from the plate current supplied to other audio amplifying tubes and means for eliminating from the signal output of the first audio tube undesired low frequency alternating currents present across the separate plate current filter which comprises a circuit arrangement for detector and first audio tubes giving a reversal of phase of signal currents between their output circuits with impedances of such relative inductive and resistive values with

reference to said undesired alternating currents, between the plates of these two tubes and a common point of connection to the separate plate current filter as to make the plate circuit impedance of the detector tube between its cathode and said common point as many times greater than the plate circuit impedance of the first audio tube between its cathode and said common point as the amplification factor between the output circuits of said tubes.

70 75

5. In electric signal amplifying apparatus having amplifying tubes connected in cascade and operated from a common source of plate potential, means for eliminating from the signal output of a pair of tubes undesired low frequency alternating currents present across the plate supply which comprises a circuit arrangement for said pair of tubes giving a reversal of phase of signal currents between their output circuits with impedances having inductive reactance of value commonly used for signal frequencies and such relative resistance values between the plates of said pair of tubes and a common connection to the plate current supply as to make the plate circuit impedance with reference to said undesired low frequencies, of the first tube between its cathode and said common point as many times greater than the plate circuit impedance, with reference to said undesired low frequencies, of the second tube between its cathode and said common point as the amplification factor of said low frequencies between the output circuits of said tubes.

80 85 90 95 100

6. In an electric amplifier for audible tone frequencies having an output tube and a preceding pair of tubes connected in cascade and operated from a common source of plate potential, means for eliminating detrimental plate circuit coupling effects between the output tube and said preceding pair of tubes comprising an impedance connecting the plate of the output tube to the plate current supply and a separate filter section for the plate current of said preceding pair of tubes adapted to prevent appreciable coupling between the output tube and said preceding pair with reference to all but very low audible frequencies and a circuit arrangement for said preceding pair of tubes giving a reversal of phase of signal currents between their output circuits with impedances having such relative ohmic values with reference to very low audible frequencies, between the plates of said pair of tubes and a common point of connection to said separate filter section as to make plate circuit impedance of the first tube of said pair between its cathode and said common point as many times greater than the plate circuit impedance of the second tube between its cathode and said common point as the amplification factor for said very low audible frequencies between the output circuits of said pair of tubes, thereby eliminating

105 110 115 120 125 130

the effect of plate circuit coupling between output tube and preceding pair with reference to very low frequencies.

7. In electric amplifying apparatus for a range of audible tone frequencies having amplifying tubes connected in cascade and operated from a common source of plate potential, the method of preventing regenerative amplification which consists in arranging circuits for successive tubes giving a reversal of phase of signal currents in their output circuits and making the effective voltage applied across the internal plate impedance of a preceding tube through plate circuit coupling a fraction, which is less than one over the amplification gain between the output circuits of said successive tubes, of the effective voltage applied across the internal plate impedance of a following tube through plate circuit coupling, for frequencies within the desired range of audible tone frequencies.

8. In electric amplifying apparatus for a range of audible tone frequencies having amplifying tubes connected in cascade and operated from a common source of plate potential, a circuit arrangement for successive tubes giving a reversal of phase of signal currents in their output circuits and means for reducing the effective voltage applied across the internal plate impedance of a preceding tube through plate circuit coupling to a value which is less than a fraction, equaling the reciprocal of amplification gain between the output circuits of said successive tubes, of the effective voltage applied across the internal plate impedance of a following tube through plate circuit coupling, for frequencies within the desired range of audible tone frequencies.

9. In an electric amplifier for low frequency alternating currents having amplifying tubes connected in cascade and operated from a common source of plate potential, an electric circuit arrangement for a pair of tubes comprising a relatively high impedance coupling unit connecting the alternating current output of the first tube to the input of the second tube and a low frequency transformer having relatively low primary impedance connected in the output circuit of the second tube, the ratio of the coupling impedance and transformer primary impedance being taken with relation to the internal plate impedances of said tubes and the amplification gain between their output circuits, and a second electric circuit arrangement for a second pair of tubes comprising a relatively high impedance coupling unit having relatively high signal load capacity connecting the signal current output of the first tube of second pair to the input of the second tube of said pair and an output coupling circuit of relatively low impedance for this last tube, the input for the second pair of tubes being connected to secondary of the transformer

having its primary connected in the output circuit of the first pair of tubes.

10. In an electric amplifier having a pair of amplifying tubes connected in cascade and operated from a common source of plate potential, means for eliminating the effect of undesired alternating currents present across the plate current supply which comprises an output device having impedance coupled through a direct current blocking condenser between the output terminals of the second amplifying tube and an external plate impedance of higher value connecting the plate of said tube to the common source of plate potential and a coupling circuit between the output of the first tube and input of the second tube having an impedance coupled through a condenser between the output terminals of said first tube and an external plate impedance of higher value connecting the plate of said first tube to said plate current supply, said external plate impedance of the first tube being of such value with reference to low frequencies relative to the external plate impedance of the second tube as to make the sum of the external and internal impedances of the first tube as many times as great as the sum of the external and internal impedances of the second tube as the amplification factor between the output circuits of said tubes.

11. In combination, an alternating current operated plate current supply device and radio receiving set having operating circuits for a detector tube and a first audio amplifier tube connected in cascade and followed by a power amplifier, means for filtering the plate current supplied to said detector tube and audio amplifier tube separate from that supplied to said power amplifier, means for reducing unwanted low frequency electric currents in the signal output of the audio amplifier tube comprising a circuit arrangement for detector and audio tubes giving a reversal of phase of signal currents between their output circuits with more than six times as much resistance effective in the external plate circuit of the detector tube as the effective resistance in the external plate circuit of said audio amplifier tube, the power amplifier circuit being balanced to eliminate from its output unwanted currents, and means for coupling the signal output of said audio tube to said power amplifier.

In testimony whereof, I hereunto affix my signature.

PHILIP H. GREELEY.
